SHOE

Fred N. La Chapelle, Beverly, Mass., assignor to Sidney H. Huberman, Boston, Mass.

Application December 8, 1941, Serial No. 422,112

3 Claims.

(Cl. 36—17)

This invention relates to shoes and more particularly to improvements in heels, heel fastening devices therefor, and sole constructions.

Objects of the invention include the provision of a new and improved filler reinforcing construction for shoe soles which may be pegged at the shank as well as in the heel area, the pegging and filler at the shank forming a rigid construction with the outsole and the pegs at the heel being capable of use to secure the heel to the heel base, outsole, and filler; the provision of a filler construction as aforesaid in which the welt strip may be sewed directly through the upper to the insole and filler, both at the heel and shank; the provision of a thick filler in a shoe sole which is skived to receive a single seam including an insole, liner, counter, upper and welt strip at the heel; and the provision of a thick sole filler forming a welt and a peg base for heels, the construction being such that a firmer heel attachment is produced without the pegs penetrating the insole, whereby no interior heel pad is necessary, as is the usual case where the heel fasteners extend through the insole and irritate the heel of the wearer in the absence of a heel pad.

Other objects of the invention include the provision of a novel heel made entirely of rubber or other plastic material, wherein the main part of the heel is molded soft rubber and the shoe pegs for fastening the heel to the filler are of hard plastic or rubber; the provision of hard rubber shoe pegs which are molded directly into a rubber heel; the provision of an all rubber heel having a thin plate for receiving shoe pegs molded therein so that no other fasteners are necessary for the heel operation; the provision of a hard plastic shoe peg whether made of rubber or commercial plastics; and the provision of an all rubber heel having molded thereinto a perforated hard rubber base plate in which are held a plurality of hard rubber pegs having relatively wide heads located between the heel and the base plate as the heel is molded so that the pegs extend outwardly of the heel in position to be set on a heel base and to be entered therein at a single straight compressing operation on a heelng machine.

Further objects of the invention reside in the provision of a sturdy long-wearing shoe sole and heel which can be assembled quickly and easily in correct aligned position relative to the upper on its last.

Other objects and advantages of the invention will appear hereinafter.

Reference is to be had to the accompanying drawings, in which:

Fig. 1 is a side view of a lasted shoe in position to be heeled, and showing the heel in place;

Fig. 2 is an enlarged bottom plan view of my novel sole showing the filler in place, with parts broken away;

Figs. 3 to 6 show sections of the insole and filler as they are applied to the last;

Fig. 7 is a bottom plan view of my improved rubber heel;

Fig. 8 is a bottom plan view of the heel plate showing the heads of the pegs;

Fig. 9 is a top plan view of the heel of Fig. 7;

Fig. 10 is a side elevation partly in section of the heel of Fig. 7;

Fig. 11 is a section on line 11—11 of Fig. 8; and

Fig. 12 is a side elevation of a woman's shoe heel made according to my invention.

In the drawings, an upper 10 is shown in Fig. 1 as lasted on last 12, the sole of the shoe being indicated at 23, the heel at 16, and the heel base at 54, the last being positioned as it would be for a heelng operation. The present invention deals mainly with the sole and heel construction of the shoe, the sole being shown in detail in Fig. 2.

The insole 20 is shown as having been channeled to produce a lip 22 which normally lies at an angle to the insole and extends toward the channeled side due to the resiliency and toughness of the leather. Lip 22 extends all around the periphery of the insole on a line evenly spaced inwards from the edge of the insole on the side thereof to which the outsole 23 is to be attached. The angled lips thus extend towards each other as they are channeled by a cut extending on an incline from a surface of the insole towards the adjacent edges thereof.

A filler block 24 of solid leather is died out to conform to the lip contour, this filler being of a width to force the lips into right angled relation with the insole as shown in Figs. 3 and 4, so that the lips exert a slight binding effect on the filler at the heel. The filler is cut to form a pair of spaced legs 26 which originally extend slightly laterally beyond the lip confines at the arch of the foot, whereby the legs resiliently force the lips at this area to stand vertically as at the heel, and therefore these parts tend to hold together for the subsequent operations without glue, although it is contemplated that an adhesive may be used. The filler block is slightly thicker than the insole, see Fig. 6.

The height of lip 22 is contemplated as being substantially the same as the thickness of the filler 24, so that a smooth surface for the outsole application is presented, but this feature may be obtained by trimming if necessary. In any case the filler is channeled as at 28 and the resultant flap 30 is lifted as shown in Fig. 4, for a stitching

operation adapted to sew the welt, upper, counter, lining, insole, and filler together with a single seam.

To this end, the upper 10, counter 32, and lining 34 are folded or bent upwards in Fig. 5 to lie parallel with and along the outer side of lip 22. A welt strip 36 is notched at 38 and positioned to fill the angle formed by the bent upper with the notch outermost. The last is then run through a curved-needle stitcher to produce the single line of stitching 40, and the six parts, filler, insole, lining, counter, upper, and welt are thus securely fastened all around the shoe at the shank and heel, leaving a straight level surface for the outsole after flap 30 is returned to its normal position.

The filler legs 26 provide a simple and convenient means for pegging the outsole to the shank of the shoe to produce a rigid construction which will not fall under use, and at the same time the pegs need not penetrate the insole, so that the foot of the wearer will not be irritated by the fastening pegs. Also, the heel area will be solid and not cave in under use to form a hollow from the inside of the shoe, thus achieving a permanently rigid heel support for the entire heel, not just at its edges.

Fig. 6 illustrates how the heel may be pegged to the filler without penetrating the insole. Peg 48, embedded in the heel, extends through heel 30 and outsole 23, stopping short of the base 54 and insole 20. A special heel for this purpose is illustrated in Figs. 7 to 12 inclusive, and this heel comprises a thin plate 46 of any desired stiff material, but preferably of hard plastic such as a hard rubber. This plate is perforated and special pegs 48 also of any desired stiff material such as hard rubber or plastic are positioned in the perforations. The pegs are provided with broad relatively flat heads 50 which are located on the side of the plate opposite a peripheral undercut 52.

When the pegs and plate are assembled, they are placed in a molding machine, and rubber forming the heel 16 is flowed around the plate and peg heads and into the plate undercut and vulcanized to form a solid rubber heel.

With the sole assembled as in Fig. 5, the outsole is applied and the last is placed in a heelng machine which is capable of exerting a high pressure on the heel area of the filler 24 by means of an anvil or the like. A heel base 54 may be adhesively applied to the filler, and a multiple drill is brought down to drill holes through the heel base, outsole, and filler, but stopping short of the insole. Material is removed to form the holes by drilling, whereas punching the holes would result in spreading the base and outsole thus causing an uneven bulging at the edges of the sole. Hence the drilling does not have this effect and a more accurate fit of the heel base on the heel area is possible. The outer edges of the holes may be enlarged slightly to form funnels for reception of the pegs 48, but in any case, after drilling, the heel 16 is merely set in place on the base 54 with each peg at the mouth of a corresponding hole, and the heelng machine is then operated to bring the anvil into play to apply pressure to the heel, thus forcing the pegs into the holes just about up to the insole but not into it. During the compression of the heel, the soft rubber will be compressed up to a certain point where it becomes substantially rigid and the force is then transmitted through the broad peg heads.

In the present case thirteen pegs are shown for fastening the heel, but more or less could be used. It is pointed out that where the holes are drilled and the pegs are forced into the holes, each peg is utilized to the same degree as all the others to obtain the holding effect, so that the heel is securely held all the way around. Where nails or other driven fasteners which make their own holes are used, they curl, bend, and otherwise become distorted so that very few of such fasteners actually hold anything, and in being clinched through the insole, nails form hard projections which injure or at least irritate the heel in the absence of a pad. Even with a pad, the clinched nail ends will often raise humps through it, especially when the pad wears. The present invention provides a construction wherein the heel is securely held to the shoe without the necessity of a heel pad and wherein the fasteners do not even enter the insole as a result of using the filler block as the holding medium. In this case the term "plastic" is used to refer to synthetic plastics, natural rubber, and artificial rubbers.

The same heelng method above described is applicable to women's top lifts as shown in general at 60 in Fig. 12. The rubber lift is molded about a thin undercut hard plastic or rubber plate 62, the latter being provided with perforations for the reception of headed hard plastic or rubber pegs 64, and the lift 60 is attached to the heel by first drilling the latter and then forcibly applying the combined lift and pegs thereto. Plastic or hard rubber pegs 65 may be used to fasten the heel itself to the insole.

Having thus described my invention and the advantages thereof, I do not wish to be limited to the details herein disclosed, otherwise than as set forth in the claims, but what I claim is:

1. In a shoe, a sole construction comprising an insole, a lip or the like attached to the insole and following the contour thereof, a relatively thick filler block secured to said lip and resting in flat parallel relation on said insole, said filler block being located substantially within the confines of said lip, an outsole lying over the filler block and lip, heel fasteners, said outsole and filler block being effective to receive said heel fasteners to secure a heel to the shoe, a heel held to said outsole and filler block by said fasteners, the latter extending through the outsole and penetrating the filler block, the outsole and filler block forming only receiving and holding means for the heel fasteners in securing the heel to the sole.

2. In a shoe, a sole construction comprising an insole, a lip on the insole following the contour thereof, a filler block thicker than the insole located in the heel area and within the lip and adapted to maintain the same in generally normal position with respect to the insole, a line of stitching securing the filler block and lip together, an outsole lying over the filler block, the latter being thick enough to receive and hold heel fasteners in cooperation with the outsole, whereby said fasteners need not penetrate the insole, a heel, fasteners extending from the heel through the filler block and outsole, said fasteners stopping short of the insole.

3. A sole construction as recited in claim 2 wherein the filler block extends from the heel area into the shank area.
